UNITED STATES PATENT OFFICE.

JOHN H. BELL, OF BROOKLYN, NEW YORK, ASSIGNOR TO COMBUSTION ENGINEERING CORPORATION, A CORPORATION OF NEW YORK.

FURNACE APPARATUS.

Application filed September 16, 1922. Serial No. 588,566.

This invention relates to furnace apparatus for boilers and the like and it is especially useful in connection with stationary boiler installations burning pulverized fuel.

5 One of the primary objects of my invention is to provide an improved means for protecting the refractories, particularly the rear or bridge wall of the combustion chamber against erosion.

10 Another object of my invention is to provide an improved arrangement of water screen for protecting the rear or bridge wall of the combustion chamber.

More specifically, my invention is directed 15 to an improved manner of connecting cooling screens in a boiler of the Stirling type.

The foregoing, together with such other objects as may hereinafter appear, or are incident to my invention I obtain by means 20 of a construction which I have illustrated in preferred form in the accompanying drawing, wherein:

Fig. 1 is a cross section through a furnace for a Stirling boiler, burning pulverized 25 fuel, in which the application of my improvements is illustrated; and Fig. 2 is a section taken on the line 2—2 of Fig. 1.

Referring now to the drawing, the combustion chamber A is substantially of the 30 vertical type having an outlet or exit for the hot products of combustion in its upper part, indicated by the reference number 7. Extending over the outlet and arranged in the path of the hot gases are a plurality of banks 35 of tubes a, b, c of a Stirling boiler. These banks of tubes are connected at their lower ends with the mud drum 8, and the upper ends of the tubes of each bank are connected to a drum 9. The banks of tubes may be 40 baffled in any suitable manner.

The pulverized fuel is introduced into the combustion chamber, preferably in a vertically downward direction, by means of one or more burners B, located so as to discharge 45 the incoming fuel adjacent the front wall 10 of the combustion chamber. About ten per cent of the air needed for combustion is supplied through the burner mechanism, the remaining air needed for combustion being supplied through the damper controlled auxiliary air inlets 11 in the front wall 10, such inlets communicating with channels 12 in the walls of the combustion chamber whereby, if desired, the auxiliary air may 50 be preheated.

The fuel and flame stream takes a U-shaped course through the combustion chamber to the outlet, the size of the combustion chamber being such that complete combustion is had therein. The bend or base of 60 the U is above the floor or bottom 13 of the combustion chamber, and the refuse not carried along in the fuel and flame stream in suspension, gravitates and deposits on the bottom 13 in ash form.

65 The temperature of the ash deposit is kept substantially below the fusion or slagging point by means of a water screen C located in the bottom of the combustion chamber and comprising two sets of tubes 14 and 15.

70 These tubes are oppositely inclined, the tubes 14 being connected at their rear ends into a header 16 and at their front ends into a header 17, while the tubes 15, at the front, are connected into the header 17 75 and at the rear into the header 18. The header 16 is connected with the mud drum 8 by means of a plurality of pipes 19, preferably arranged in groups of three each at the ends of the header 16.

80 The number of these pipes, however, may be varied as the demands of the particular installation may require. The upper ends of the pipes 19 project just above the bottom of the mud drum 8 so as to clear mud and scale which 85 may collect therein. The header 18 is connected with the mud drum 8 similarly by two groups of tubes 20, preferably three in number for each group. The upper ends of the tubes 20, however, extend well toward 90 the top of the mud drum. A circulation is thus had through the water screen C and the screen operates to reduce the temperature of the deposit by absorbing radiant heat therefrom.

95 The header 17 is preferably anchored and expansion of the water screen tubes takes place toward the rear.

In order to prevent washing away of the rear or bridge wall 21 by the melting and 100 running down of the deposit thereon, I provide a cooling screen D composed of tubes 22, the lower ends of which are connected into the header 18 and the upper ends connected into the mud drum. The tubes 22 are 105 bent as illustrated, and therefore, expansion and contraction are automatically taken care of.

110 Circulation takes place through the screen D and it functions to cool the deposit on

the rear wall which deposit builds out in the form of "whiskers" or threads. This deposit, if cooled, will naturally break off when the "whiskers" have built out sufficiently to cause breaking off by their overhanging weight. The tubes 22 are spaced sufficiently far from the bridge wall to permit the deposit to fall freely to the bottom. The deposit between tubes will, of course, fall 10 to the bottom.

In addition to preventing the formation of slag, the screens increase the efficiency of the furnace in the generation of steam and while, of course, they have a chilling 15 effect, the lowering of temperature in the combustion chamber is a useful one as it results from the absorption of heat which is employed in generating steam. The need of employing excess air is avoided in which 20 connection it is to be pointed out that the use of excess air lowers the furnace temperature to no useful purpose and increases the volume of gas which must be handled and imposes limitations on the efficiency and 25 CO₂ attainable, which limitations may be exceeded where cooling screens are employed.

The arrangement is simple, the parts are easy to install and are readily accessible.

30 The tubes 20, which are few in number, relieve the header 18 of some of the steam created in the lower screen C, whereby less steam in proportion to water enters the tubes 22 from the header 18.

35 Other advantages will occur to those skilled in the art.

What I claim is:

1. In combination with a furnace and its boiler, a combustion chamber; a cooling 40 screen exposed to radiant heat in the lower portion of the combustion chamber comprising two sets of tubes, a header with which both sets are connected at one end, and a header for the other end of each set; means 45 connecting the last mentioned two headers into the circulation of the boiler; and a cooling screen exposed to radiant heat adjacent a vertical wall of the combustion chamber connected with one of the headers and with 50 the boiler.

2. In combination with a furnace and its boiler, a combustion chamber; a cooling 55 screen exposed to radiant heat in the lower portion of the combustion chamber comprising two sets of oppositely inclined tubes, a header with which both sets are connected at one end, and a header for the opposite end of each set; means connecting the last mentioned two headers into the circulation of the 60 boiler; and a cooling screen exposed to radiant heat adjacent a vertical wall of the chamber connected with one of said last two headers and with the boiler.

3. In combination with a furnace and its

boiler, a combustion chamber; a cooling 65 screen exposed to radiant heat in the lower portion of the combustion chamber comprising two sets of tubes, a header with which both sets are connected at one end, and a header for the other end of each set; means 70 connecting the last mentioned two headers into the circulation of the boiler; and a second cooling screen exposed to radiant heat connected 75 with one of said headers and the boiler.

4. In combination with a furnace and its boiler, a combustion chamber; a cooling screen exposed to radiant heat in the lower portion of the combustion chamber composed 80 of tubes and headers and connected in the circulation of the boiler; and a second cooling screen exposed to radiant heat connected with one of said headers and with the boiler.

5. In combination with a furnace and its boiler, a combustion chamber; a cooling 85 screen exposed to radiant heat in the lower portion of the combustion chamber composed of tubes and headers and connected in the circulation of the boiler; and a second cooling screen exposed to radiant heat connected 90 with one of said headers and with the boiler, said tubes being bent.

6. In combination with a furnace and its boiler, a combustion chamber; a cooling 95 screen exposed to radiant heat in the lower portion of the combustion chamber composed of tubes and headers and connected in the circulation of the boiler and a second cooling screen exposed to radiant heat connected with one of said headers and with the boiler, 100 said tubes being bent and one of said headers being anchored.

7. In combination a boiler and its furnace, said boiler having a lower drum and an upper drum and a plurality of tubes connecting 105 said drums; a row of relatively closely spaced water tubes extending along an upright wall of the furnace and exposed to radiant heat, downcomer means leading from the lower drum of the boiler for supplying said tubes with water, said tubes being connected at their upper ends to deliver into the said lower drum of the boiler.

8. In combination a boiler and its furnace, 115 said boiler having a lower drum and a plurality of upper drums and a plurality of tubes connecting the upper drums with the lower drum, a row of relatively closely spaced water tubes extending along an upright wall of the furnace and exposed to radiant heat, downcomer means leading from the lower drum of the boiler for supplying said tubes with water, said tubes being connected at their upper ends to deliver into the 120 said lower drum of the boiler.

In testimony whereof, I have hereunto signed my name:

JOHN E. BELL.
